(57) **ABSTRACT**

Headwear includes a crown of planar fabric panels sewn together in-plane, a brim and a size adjuster of a strip of fabric on a lower portion of the crown, around an entirety of a circumference of the crown or a part of the circumference of the crown. The size adjuster includes, in a space defined by a casing formed by the strip of fabric, a shape-changeable component that, at heat of a predetermined temperature or higher, is configured to soften and extend in a circumferential direction of the crown by a length that is greater than a length by which the shape-changeable component extends at heat lower than the predetermined temperature, in response to a tensile force applied to the shape-changeable component in the circumferential direction of the crown. The fabric panels have a contour and a mesh formed by cutting fabric on a bias.

FIG. 1

FIG. 2

FIG. 3

FIG. 4

1
HEADWEAR

**CROSS REFERENCE TO RELATED
APPLICATIONS**

The present application is based on and claims priority of Japanese Patent Application No. 2022-004215 filed on Jan. 14, 2022. The entire disclosure of the above-identified application, including the specification, drawings, and claims is incorporated herein by reference in its entirety.

FIELD

The present invention relates to headwear.

BACKGROUND

Conventionally, headwear where the circumferential size of the crown is adjustable has been proposed. Japanese Unexamined Patent Application Publication No. 2021-088800 (hereinafter, “JP 2021-088800”) discloses headwear that is adjustable in size by an elastic band provided to a sweat receiving portion.

SUMMARY

Technical Problem

However, it is difficult to adjust the size of the headwear disclosed in JP 2021-088800 by a sufficient length.

In view of this, the present invention provides headwear that can be adjusted in size by a sufficient length.

Solution to Problem

In order to overcome the above-described technical problem, headwear according to one aspect of the present invention includes a crown of planar fabric panels sewn together in-plane, and a brim. The headwear includes a size adjuster of a strip of fabric, the size adjuster being provided on a lower portion of the crown, around an entire circumference or part of the circumference of the crown. The size adjuster includes, in a space defined by a casing formed by the strip of fabric, a shape-changing component that extends in a circumferential direction of the crown by a predetermined length by heat of a predetermined temperature or higher. Each of the fabric panels, the strip of fabric, or each of the fabric panels and the strip of fabric has a contour and a mesh formed by cutting fabric on a bias. At least one of the following are sewn together using elastic thread: (1) the fabric panels; (2) the crown and the brim; and (3) the crown and the size adjuster.

BRIEF DESCRIPTION OF DRAWINGS

These and other advantages and features will become apparent from the following description thereof taken in conjunction with the accompanying Drawings, by way of non-limiting examples of embodiments disclosed herein.

FIG. 1 is a perspective view illustrating the entire headwear according to an exemplary embodiment.

FIG. 2 is a side view illustrating the entire headwear according to an exemplary embodiment.

FIG. 3 illustrates the entire circumference of a size adjuster of the headwear according to an exemplary embodiment.

2

FIG. 4 illustrates a shape-changing component of the headwear according to an exemplary embodiment.

DESCRIPTION OF EMBODIMENT(S)

The headwear according to the present invention includes a size adjuster of a strip of fabric, the size adjuster being provided on a lower portion of the crown, around an entire circumference or part of the circumference of the crown. 10 The size adjuster includes, in a space defined by a casing formed by the strip of fabric, a shape-changing component that extends in a circumferential direction of the crown by a predetermined length by heat of a predetermined temperature or higher. In the headwear according to the present invention, each of the fabric panels, the strip of fabric, or each of the fabric panels and the strip of fabric has a contour and a mesh formed by cutting fabric on a bias, and is sewn together using elastic thread. With this configuration, in the headwear according to the present invention, the size of the crown can be adjusted by a sufficient length, for example, over a length of approximately six centimeters or more, from approximately 55 centimeters to approximately 61 centimeters or more.

25
Embodiment

Hereinafter, an exemplary embodiment will be described with reference to the drawings.

30
Structure

FIG. 1 is a perspective view illustrating the entire headwear 1 according to an exemplary embodiment. Headwear 1 includes crown 10 and brim 20. As used herein, crown 10 refers to the part of headwear 1 that covers the wearer's head, i.e., the side and top surfaces of headwear 1. Brim 20 refers to the part of headwear 1 that protrudes outward from crown 10.

40 The fabric of headwear 1 may be made of cotton, wool, hemp, a plant-based material, or a synthetic fiber such as polyester, and is a textile that forms the outer surface of headwear 1. The fabric may be, for example, felt fabric or knitted fabric. The fabric may be made from a single sheet of fabric or made from a plurality of fabric panels 11.

Crown 10 of headwear 1 includes size adjuster 30 and one or more eyelets 40. Crown 10 is made of a plurality of planar fabric panels 11 sewn together in-plane.

Size adjuster 30 is a strip of fabric provided on the lower portion of crown 10, around the entire circumference or part of the circumference of crown 10. Size adjuster 30 may be attached to the inside of the perimeter forming the lower portion of crown 10, and, as illustrated in FIG. 1, may be integral with crown 10 so as to form the lower portion of crown 10.

50 Note that crown 10 of headwear 1 does not include a sweatband. As used herein, a sweatband refers to a strip of fabric provided on the inside of crown 10, around the entire circumference of crown 10.

60 FIG. 2 is a side view illustrating the entire headwear 1 according to an exemplary embodiment. Size adjuster 30 may have the shape of a 2 cm wide strip. For example, size adjuster 30 may be provided on the lower portion of the back of crown 10. More specifically, size adjuster 30 may be provided in an area of crown 10 where crown 10 does not contact brim 20, in the shape of a 2 cm wide strip at the lower edge of crown 10.

The one or more eyelets **40** included in crown **10** may be provided one per fabric panel **11** of crown **10**. For example, when crown **10** includes six fabric panels **11**, since each of the six fabric panels **11** includes one eyelet **40**, headwear **1** includes a total of six eyelets **40**.

FIG. 3 illustrates the entire circumference of size adjuster **30** of headwear **1** according to an exemplary embodiment. FIG. 3 is a view of headwear **1** from below. As illustrated in FIG. 3, size adjuster **30** may be provided around the entire circumference of the lower portion of crown **10**. For the sake of convenience, size adjuster **30** is illustrated in FIG. 3 with its width projected as-is.

Size adjuster **30** may be formed from fabric cut into a strip, and the fabric cut into a strip may be sewn into a casing. Size adjuster **30** includes, provided in the space defined by the casing formed by the strip of fabric, shape-changing component **31** that extends in the circumferential direction of crown **10** by a predetermined length by heat of a predetermined temperature or higher.

Stated differently, headwear **1** includes a strip of fabric sewn so as to form a casing on the lower portion of crown **10**, and includes a core inside the sewn casing of the strip of fabric. Here, the core is shape-changing component **31** that extends in the circumferential direction of crown **10** by a predetermined length by heat of a predetermined temperature or higher.

Rather than the circumferential direction of crown **10**, shape-changing component **31** may extend in, for example, a direction perpendicular to the circumferential direction of crown **10**. Shape-changing component **31** may extend in every direction by heat of a predetermined temperature or higher.

Each fabric panel **11** of crown **10** and/or the strip of fabric of size adjuster **30** has a contour and mesh formed by cutting on the bias, and is sewn with an elastic thread. In other words, each fabric panel **11** of crown **10** and/or the strip of fabric of size adjuster **30** is formed using textile cut on the bias.

As used herein, cutting on the bias means cutting the fabric at a 45 degree angle relative to the warp or weft. Note that cutting on the bias is not limited to cutting exactly at 45 degrees, and includes cuts made at an angle to the warp or weft. With this, each fabric panel **11** of crown **10** and/or the strip of fabric of size adjuster **30** is more elastic than when cut using a normal cutting method.

FIG. 4 illustrates shape-changing component **31** of headwear **1** according to an exemplary embodiment. FIG. 4 is a partial view of only size adjuster **30** of headwear **1** and shape-changing component **31** included in size adjuster **30**.

As described above, shape-changing component **31** extends in the circumferential direction of crown **10** by a predetermined length by heat of a predetermined temperature or higher. In other words, shape-changing component **31** is a component that can change in shape by reaching a predetermined temperature or higher. More specifically, by reaching a predetermined temperature or higher, shape-changing component **31** can extend in the direction in which tensile force is applied to shape-changing component **31**. Here, the predetermined temperature may be, for example, 28 degrees Celsius. For example, shape-changing component **31** starts to soften at 28 degrees Celsius.

For example, shape-changing component **31** may extend a few centimeters to approximately six centimeters in the circumferential direction of crown **10** in response to body heat from the head of the wearer contacting size adjuster **30**. Stated differently, shape-changing component **31** may extend, for example, a few centimeters to approximately six

centimeters or more in the circumferential direction of crown **10** when subjected to a temperature approximately equal to the body temperature of the head of the wearer. In other words, by shape-changing component **31** extending approximately six centimeters or more, the circumferential size of crown **10** of headwear **1** can be changed from approximately 55 centimeters to approximately 61 centimeters, for example.

At a predetermined temperature or higher, shape-changing component **31** extends in the circumferential direction at a rate according to the tensile force applied to shape-changing component **31** in the circumferential direction. For example, shape-changing component **31** may extend in the circumferential direction of crown **10** due to the body heat of the wearer according to the tension in shape-changing component **31** brought about by the pressure from the wearer's head on size adjuster **30** when the wearer puts headwear **1** on their head.

For example, when shape-changing component **31** is subjected to a temperature approximately equal to the body temperature of the wearer's head, size adjuster **30** extends in the circumferential direction of crown **10** just long enough in the direction in which size adjuster **30** is pulled to conform to the wearer's head to allow size adjuster **30** to conform to the wearer's head.

Shape-changing component **31** remains extended in the circumferential direction of crown **10** while a temperature greater than or equal to the predetermined temperature is kept constant. For example, since the temperature of shape-changing component **31** is kept constant at a predetermined temperature or higher by the body heat of the wearer while the wearer's head is contacting size adjuster **30**, shape-changing component **31** remains extended in the circumferential direction at a rate according to the tensile force applied to shape-changing component **31** in the circumferential direction.

For example, once shape-changing component **31** has extended in the circumferential direction of crown **10** in response to the body heat of the wearer, while size adjuster **30** is in contact with the wearer's head and subjected to a temperature approximately equal to the body temperature of the wearer's head, shape-changing component **31** maintains the circumferential extension of crown **10**.

At least one of the following are sewn together using elastic thread **32**: (1) fabric panels **11**; (2) crown **10** and brim **20**; and (3) crown **10** and size adjuster **30**. Headwear **1** may be sewn together entirely with elastic thread **32**. As used herein, elastic thread is, for example, woolly thread.

With this, when shape-changing component **31** is extended in the circumferential direction of crown **10**, even if tension is exerted on size adjuster **30** and exerted between fabric panels **11** of crown **10** that are sewn to size adjuster **30**, fabric panels **11** and size adjuster **30** and the like can extend slightly as a result of elastic thread **32** stretching. In other words, when shape-changing component **31** is extended in the circumferential direction of crown **10**, headwear **1** can accommodate tension exerted on the entire headwear **1**.

For example, when shape-changing component **31** is extended in the circumferential direction of crown **10**, the strip of fabric of size adjuster **30** extends as shape-changing component **31** extends. Fabric panels **11** forming crown **10** that are stitched to the strip of fabric extend a certain amount as the strip of fabric extends. At this time, elastic thread **32** that stitches the strip of fabric and fabric panels **11** together also stretches as the strip of fabric extends. With this, as a result of the entire headwear **1** extending as shape-changing

5

component 31 extends, the size of headwear 1 can be adjusted significantly more than conventional configurations.

ADVANTAGES

Headwear 1 according to an exemplary embodiment includes crown 10 of planar fabric panels 11 sewn together in-plane, and brim 20. Headwear 1 includes size adjuster 30 of a strip of fabric, size adjuster 30 being provided on a lower portion of crown 10, around an entire circumference or part of the circumference of crown 10. Size adjuster 30 includes, in a space defined by a casing formed by the strip of fabric, shape-changing component 31 that extends in a circumferential direction of crown 10 by a predetermined length by heat of a predetermined temperature or higher. Each of fabric panels 11, the strip of fabric, or each of fabric panels 11 and the strip of fabric has a contour and a mesh formed by cutting fabric on a bias. At least one of the following are sewn together using elastic thread: (1) fabric panels 11; (2) crown 10 and brim 20; and (3) crown 10 and size adjuster 30.

With this configuration, in headwear 1 according to an exemplary embodiment, when size adjuster 30 is subject to a predetermined temperature or higher, size adjuster 30 can sufficiently extend as a result of shape-changing component 31 extending by a predetermined length, and the entire headwear 1 can also sufficiently extend so as to coincide. When shape-changing component 31 extends by a predetermined length, the extension of headwear 1 according to an exemplary embodiment coinciding with the extension of shape-changing component 31 is not hindered by the stitching of all the parts that form headwear 1. Accordingly, headwear 1 according to an exemplary embodiment can adjust its size by a sufficient length.

In headwear 1 according to an exemplary embodiment, at a predetermined temperature or higher, shape-changing component 31 extends in the circumferential direction at a rate according to the tensile force applied to shape-changing component 31 in the circumferential direction.

With this configuration, when size adjuster 30 is subjected to the body heat of the wearer's head, headwear 1 according to an exemplary embodiment can adjust its size so as to fit the size of the wearer's head. Accordingly, headwear 1 according to an exemplary embodiment can adjust its size by a sufficient length.

In headwear 1 according to an exemplary embodiment, shape-changing component 31 remains extended in the circumferential direction of crown 10 while a temperature greater than or equal to the predetermined temperature is kept constant.

With this configuration, while size adjuster 30 is subjected to the body heat of the wearer's head, headwear 1 according to an exemplary embodiment can maintain the size adjust-

6

ment of headwear 1 so as to fit the size of the wearer's head. Accordingly, headwear 1 according to an exemplary embodiment can adjust its size by a sufficient length.

Hereinbefore, headwear 1 according to the present invention has been described based on an exemplary embodiment, but the present invention is not limited this exemplary embodiment. Various modifications of the exemplary embodiment as well as embodiments resulting from arbitrary combinations of elements of different exemplary embodiments that may be conceived by those skilled in the art are intended to be included within the scope of the present invention as long as they do not depart from the essence of the teachings of the present invention.

15 The invention claimed is:

1. Headwear comprising:
a crown of planar fabric panels sewn together in-plane;
a brim; and
a size adjuster of a strip of fabric, the size adjuster being
on a lower portion of the crown, around an entirety of
a circumference of the crown or a part of the circum-
ference of the crown,

wherein:

the size adjuster includes, in a space defined by a casing
formed by the strip of fabric, a shape-changeable
component that, at heat of a predetermined temperature
or higher, is configured to soften and extend in a
circumferential direction of the crown by a length that
is greater than a length by which the shape-changeable
component extends at heat lower than the predeter-
mined temperature, in response to a tensile force
applied to the shape-changeable component in the
circumferential direction of the crown;

the fabric panels have a contour and a mesh formed by
cutting fabric on a bias such that a direction of the
contour and a direction of the mesh intersect at an acute
angle; and

the fabric panels are sewn together using elastic thread,
the crown and the brim are sewn together using elastic
thread, or the crown and the size adjuster are sewn
together using elastic thread.

2. The headwear according to claim 1, wherein
the shape-changeable component is configured to remain
extended in the circumferential direction of the crown
while a temperature greater than or equal to the pre-
determined temperature is kept constant.
3. The headwear according to claim 1, wherein
the fabric panels are sewn together using elastic thread,
the crown and the brim are sewn together using elastic
thread, and the crown and the size adjuster are sewn
together using elastic thread.
